Filed Nov. 19, 1959, Ser. No. 58,406

Term of patent 7 years

(Cl. D85—2)

FIG 1

The sides opposite those shown are substantially the same in appearance as the sides shown.

The representations of cigarettes on the outside walls are embossed.

I claim:

The ornamental design for an ash tray, substantially as shown and described.
